INVENTOR

UNITED STATES PATENT OFFICE

96,968

DESIGN FOR A DRESS

Abraham Greenspan, New York, N. Y.

Application August 20, 1935, Serial No. 58,207

Term of patent 3½ years

To all whom it may concern:

Be it known that I, Abraham Greenspan, a citizen of the United States of America, residing in Manhattan, county of New York, and State of New York, have invented a new, original, and ornamental Design for a Dress, of which the following is a specification, reference being had to the accompanying drawing, forming part thereof, wherein,

The collar and vestee portion of the dress, have shirred piping thereon, and which collar and vestee portion is edged off with straight piping.

I claim:

The ornamental design for a dress, substantially as shown, and described.

ABRAHAM GREENSPAN.
